UNITED STATES PATENT OFFICE.

LOTT FREDERICK, OF INDIANA, PENNSYLVANIA, ASSIGNOR OF SIX-TWELFTHS TO GEORGE CONRATH, B. W. STEWART, HARRY BELL, R. V. KERR, GEORGE M. APPLEBY, J. R. APPLEBY, FRANK KRING, MATTHEW RAY, WILLIS GETTY, R. J. MARSHALL, H. T. ANDERSON, AND F. W. KERR, ALL OF INDIANA, PENNSYLVANIA.

ROAD-CROSSING.

No. 921,228.

Specification of Letters Patent.

Patented May 11, 1909.

Application filed February 9, 1908. Serial No. 476,913.

To all whom it may concern:

Be it known that I, LOTT FREDERICK, citizen of the United States, residing at Indiana, in the county of Indiana and State of Pennsylvania, have invented certain new and useful Improvements in Road-Crossings; and I do hereby declare the following to be a full, clear, and exact description of the invention, such as will enable others skilled in the art to 10 which it appertains to make and use the same.

My invention relates to new and useful improvements in road crossings and more particularly to that class adapted to be used 15 in connection with railways to form a convenient crossing for vehicles and my object is to provide means for attaching frames or the like to opposite sides of the track rails, whereby the vehicle may pass thereover 20 without unnecessary jar.

A further object is to provide means for securing the frames in position and a still further object is to provide means for containing a suitable filling between the frames on 25 the inner faces of the track rails.

Other objects and advantages will be hereinafter referred to and more particularly pointed out in the claim.

In the accompanying drawings forming 30 part of this application, Figure 1 is a top plan view of a section of track-way showing my improved crossing attached thereto. Fig. 2 is a side elevation of the crossing. Fig. 3 is a sectional view as seen on line 3--3, Fig. 1, 35 Fig. 4 is a sectional view as seen on line 4--4, Fig. 1, and Fig. 5 is a sectional view as seen on line 5--5, Fig. 1.

In the drawings in which similar reference numerals designate corresponding parts 40 throughout the several views, 1 indicates track rails, which are constructed in the usual manner and which are secured upon cross ties 2 by means of spikes or the like 3. Positioned at the inner and outer sides of the 45 rails 1 are metallic frames 4 and 5, respectively, said frames comprising top plates 6 and 7, respectively and side walls 8 and 9 and end walls 10 and 11, respectively, the side walls 8 and 9 being preferably vertical, while 50 the end walls 10 and 11 are preferably inclined, the object in inclining said end walls being to prevent the possibility of parts of

the train from catching on the metallic frames as the train passes thereover.

The top plates 6 and 7 are preferably 55 slightly inclined downwardly from the point of their intersection with the rail head to their outer edges, so that the entire weight of a vehicle passing over the metallic frame will not rest directly thereon, but will simultaneously engage the tops of the rails, and the free edges of the end walls 10 and 11 are provided with projections 12 and 13, which are adapted to fit closely the contour of the head and base of the rail and rest against the 60 web of the rail, thereby forming a close connection between the metallic frames and the rails with which they are engaged.

The lower edges of the side and end walls of the metallic frames are provided with 70 flanges 14, which rest upon the cross ties 2 and are secured thereto by means of spikes 15, that portion of the flanges extending along the end walls having raised portions 16, which portions are adapted to fit over the 75 base of the rail and are secured thereto by means of spikes 17, said raised portions not only serving to brace the rails, but permitting a snug fit of the metallic members with the rails.

The inner metallic frames 4 are provided with channels 18, which channels are adapted to rest adjacent the edges of the rails 1 to permit the flanges of the wheels of the train to pass over the metallic frames without engaging the same, the channels at their ends being flared away from the rails as shown at 85 19 to prevent any possibility of the flanges striking the ends of the frame members as the wheels are passing into the channels.

The free edges 20 of the channels 18 engage the face of the rails 1 at a point slightly above the lower edges of the heads of the rails, thereby preventing any possibility of obstructions catching or passing between the 95 rails and the edges 20 and also preventing the toe and heel plates on the shoes of the animals passing over the frames from being caught therein and to prevent the animals from slipping when traveling over the frames, 100 the top plates 6 and 7 are provided with suitable ribs 21, which project slightly above the faces of the plates and form a more or less roughened surface.

The space 22 between the metallic frames 4 may be filled with any suitable form of ballast or an additional plate or plates may be provided to cover this space.

To prevent chains or other depending portions of the cars from catching on the parts between the metallic frames 4, I provide guards 23, which are placed in alinement with the ends of the metallic frames and at the same inclination as the inclination of the end walls 10, the upper end of the guards having curved terminals 24, which are substantially semi-circular in cross section and engage curved lugs 25 on the side walls of the metallic frames 4, the lower ends of the guards having flanges 26, which rest upon the ties 2 and are secured thereto by means of spikes 27.

As shown by dotted lines in Fig. 4, the metallic frames may be reinforced as when heavy vehicles are constantly passing over the crossing by placing brackets or braces 28 below the top plates and against the side walls 8, or said brackets may be arranged in any suitable manner.

By forming the frames of metal, they can be made in any length and angle or may be curved to fit any curvature of the track, thereby adapting the same to be applied to use at any point along the line of railway where a street or road crossing is encountered.

It will likewise be seen that the frames

may be readily removed to replace the ties and by fitting the plates snugly to the rails as shown, water will be prevented from entering between the rails and frames in any extent, thereby protecting and preserving the ties. It will likewise be seen that by providing the metallic frames they will be practically indestructible and may be moved from place to place as occasion may require.

What I claim is:

In a crossing construction for railway tracks, the combination with track rails: of metallic frames fitting snugly the opposite sides of the rails and conforming to the shape thereof, the metallic frames on the inner faces of the rails having channels therein, the end portions of which are flared, the upper faces of the frames having ribs thereon, means to secure the frames in position adjacent the rails, guards between the frames on the inner faces of the rails and at the ends thereof, the upper ends of said guards having curved terminals and lugs on the frames with which said terminals engage, the ends of the frames and the guards being inclined.

In testimony whereof I have signed my name to this specification in the presence of two subscribing witnesses.

LOTT FREDERICK.
